CATHODE RAY TUBE

Max Knoll, Berlin, Germany, assignor to Telefunkens Gesellschaft für Drahtlose Telegraphie m. b. H., Berlin, Germany, a corporation of Germany

Application July 26, 1934, Serial No. 737,023
In Germany July 31, 1933

2 Claims. (Cl. 250—163)

This invention relates to a cathode ray tube which can be used as receiver for purposes of television, and which has the advantage over the tubes hitherto known for this purpose, that the current impinging on the luminescent screen can be varied by means of considerably smaller voltages.

5 This invention is related to my co-pending applications 737,022, filed July 26, 1934, and entitled "Cathode ray tube", and 737,024 filed July 26, 1934, and entitled "Cathode ray tube."

To this end, and in accordance with the invention, a grid is to be placed in front of the cathode of the tube, possessing against the cathode a constant positive potential, and furthermore at a larger distance from the cathode a second grid is provided having negative potential as regards the first mentioned grid, the value of this potential varying in dependence upon the voltage serving 10 for the modulation of the brightness of the luminescent spot.

Referring to the drawing in which embodiment of the invention is schematically illustrated, my invention will now be described in detail.

25 The cathode of the cathode ray tube is designated by 10, while 11 represents a disk galvanically connected thereto. At a small distance from the cathode a grid 12 is disposed charged, for instance, by a potential +100 volts against the cathode, and below the said grid a further grid 13 is placed having a negative potential against the first mentioned grid, whereby the latter potential changes depending upon the modulation of the brightness of the luminescent spot. Below grid 30 13 a third grid 14 is provided to which may be applied a positive potential of 2000 volts against the cathode. Grid 14 represents the anode of the cathode ray tube. In place of grid 14, an anode shutter may likewise be used having but a single 35 opening.

The functioning of the arrangement is such, that the cathode rays are accelerated by the grid 12, while in the space between grid 12 and grid 13 a decrease of the velocity occurs. The quantity 40 of electrons passing through grid 13 depends

upon the respective potential difference between grid 13 and grid 12. As tests have shown, the arrangement according to the invention affords obtaining a variation of the luminosity of the luminous spot on the screen of the tube, within 5 wide limits, with considerably lower modulation voltages at grid 13, than was possible in the hitherto known arrangements. The grid 12 can be considered a virtual source of electrons from which electrons are already emitted at finite 10 velocity.

Having thus described the invention, what I claim is:

1. In a cathode ray tube the combination of a thermionic emitter, a plane electrostatic guard 15 electrode connected thereto and lying in the same plane as the emitting surface of the emitter, an accelerating electrode positioned parallel to and co-axial to the guard electrode and adapted to be maintained at positive potential relative to 20

said cathode, a second accelerating electrode adapted to be maintained at a positive potential with respect to the first said accelerating electrode, and a modulating electrode extending parallel to and co-axial to the first and second accelerating electrodes and positioned intermediate 25 said accelerating electrodes.

2. In a cathode ray tube the combination of a thermionic emitter, a plane electrostatic guard 30 electrode connected thereto and lying in the same plane as the emitting surface of the emitter, a plane perforated accelerating electrode positioned parallel and co-axial to said guard electrode and adapted to be maintained at a positive potential 35 relative to said cathode, a second perforated accelerating electrode positioned in spaced relationship with respect to said first electrode and adapted to be maintained at a positive potential with respect to said first accelerating electrode, 40 and a modulating electrode extending parallel to and co-axial with said accelerating electrodes and located intermediate said accelerating electrodes.
